(57) **CLAIM**

We claim the ornamental designs for a helical implant, as shown and described.

DESCRIPTION

FIG. 1 is a perspective front view of the helical implant; FIG. 2 is a perspective top view of the helical implant of FIG. 1; FIG. 3 is a perspective bottom view of the helical implant of FIG. 1; FIG. 4 is a side view of a first side of the helical implant of FIG. 1; FIG. 5 is a side view of a second side of the helical implant of FIG. 1; FIG. 6 is a side view of a third side of the helical implant of FIG. 1; FIG. 7 is a side view of a fourth side of the helical implant of FIG. 1; FIG. 8 is a top view of the helical implant of FIG. 1; and, FIG. 9 is a bottom view of the helical implant of FIG. 1. The broken lines in the drawings illustrate portions of the helical implant which form no part of the claimed design.

1 Claim, 4 Drawing Sheets
